FIG. 1.

INVENTOR.
Louis A. Safford
or Emil Starek
ATTORNEY.

UNITED STATES PATENT OFFICE.

LOUIS A. SAFFORD, OF ST. LOUIS, MISSOURI.

PISTON-RING.

1,391,795.

Specification of Letters Patent. Patented Sept. 27, 1921.

Application filed September 8, 1919. Serial No. 322,345.

To all whom it may concern:

Be it known that I, LOUIS A. SAFFORD, a citizen of the United States, residing at St. Louis, State of Missouri, have invented certain new and useful Improvements in Piston-Rings, of which the following is a full, clear, and exact description, reference being had to the accompanying drawings, forming a part hereof.

10 The present invention is directed to improvements in piston-rings for use in cylinders of internal combustion engines, and particularly to the closed joint type of split ring, the improved ring being distinguished 15 from both the step joint and the miter joint varieties of ring by reason of the plurality of lapped surfaces disposed across the ring when the ring is contracted to working size or the size it assumes in the cylinder in 20 which it is intended to operate. In the type of engine referred to (internal combustion) where the piston is driven from one end of the cylinder by highly heated gases having great expansive force, it is eminently desirable 25 to have a one-piece piston-ring which will offer to these gases a maximum impediment to their passage past the ring with successive explosions on the drive strokes, or on the compression strokes before explosion; and in order to prevent the gases from flowing past the ring it is necessary to employ 30 a ring with a joint which shall serve as an effective barrier against such flow. To provide a joint which will effectively and 35 to the necessary degree arrest the flow of the gases past the ring is the main object of the invention; a further object being to provide a ring which may be manufactured at reasonable cost, and one possessing further and 40 other advantages better apparent from the following detailed description in connection with the accompanying drawings in which—

Figure 1 represents a middle longitudinal section of a gas engine cylinder with the 45 piston in elevation showing the improved ring applied thereto; Fig. 2 is an outer face view of the piston ring when free or expanded; Fig. 3 is an outer face view of the ring when contracted or compressed to 50 working size; Fig. 4 is an enlarged end view of one of the terminals of the ring; Fig. 5 is an enlarged end view of the opposite terminal; Fig. 6 is an enlarged outer face view of a portion of the ring showing 55 the lap joints formed by compressing the ring to working size; Fig. 7 is a side view of one-half of the piston ring when in the free state; Fig. 8 is a side view of one-half of the ring when compressed to working size; Fig. 9 is an enlarged outer face view of a portion of a ring in the free state showing a modified construction of terminals; Fig. 10 is an end view of one of the terminals of the ring shown in Fig. 9; Fig. 11 is an end view of the opposite terminal of the ring shown in Fig. 9; Fig. 12 is an outer face view of a portion of a ring compressed to working size showing an angle of inclination for the oblique lap-joint of substantially thirty (30) degrees; Fig. 13 is a similar view showing an oblique lap joint inclined at an angle of less than thirty (30) degrees; and Fig. 14 is a similar but enlarged view of a ring slightly compressed showing further modifications of terminals and joints resulting therefrom.

Referring to the drawings, and for the present to Figs. 1 to 8 inclusive, C represents the engine cylinder, and P the piston which, in the present example, is shown 80 equipped with two of the improved piston rings. The ring comprises a resilient outwardly springing split metal band 1 having axially parallel inner and outer faces, and of substantially rectangular cross-section, 85 the ends of the band being normally disengaged or separated when the band is free or in the open (Figs. 2, 7.) As well understood in the art, the band is received by a peripheral groove h formed in the piston 90 (Fig. 1.) Each end of the band terminates in a tongue t flush with one side of the band and of the thickness of the band, and in a recess or depression d offset from the opposite side of the band and of substantially the same dimensions as the tongue, the 95 tongue of one terminal being on the same side of the band as the recess of the opposite terminal, whereby with a compression of the band to working size the tongue is received by said recess as clearly apparent from Figs. 3, 6 and 8 of the drawings. The thickness of the tongue t is equal to the depth of the offset n forming the end wall of the recess d, the free edge of the bottom wall of the recess 100 being connected to the base of the tongue t by an inclined plane face e making with the planes of the inner face of the tongue and the bottom wall of the recess the equal angles i, which, upon compression of the 105 ring to working size become alternate angles 110 (Figs. 3, 6,) said angles in the present ex-

ample being substantially forty-five (45) degrees. When the ring is compressed to working size, the inclined and parallel faces *e* form between them an inclined or diagonal 5 lap joint *a*, the ends whereof communicate with the parallel lap joints *a'*, *a'*, formed respectively by the overlapping of the opposing faces of the tongues *t* and bottoms of the recesses *d*, the outer ends of the joints *a'* 10 having leading therefrom the parallel butt joints *a'*, *a'*, formed by the offsets *n* and the free ends of the tongues *t*, the joints *a''* opening through the sides of the piston ring. There thus results a compound zig-zag or *Z*- 15 shaped joint comprising the individual joints *a''*, *a'*, *a*, *a'*, *a''*, the lap joints *a'*, *a'*, being parallel and disposed in planes transverse and at right angles to the axis of the ring, and the butt joints *a''*, *a''*, being parallel and preferably (though not necessarily) 20 parallel to said axis, the lap joint *a* being at an incline to the axis of the ring and oblique to the sides of the ring as shown. The joints offering the most effective resistance to the 25 passage of the gases past the piston ring are the parallel lap joints *a'*, *a'*, between the tongues *t* and bottoms of the recesses *d*, the gases obviously meeting with considerably less resistance in their passage through the 30 joints *a*, *a''*, the ring never being completely closed when compressed to working size (Figs. 3, 6,) so that while the walls or faces forming the joints *a'*, *a'*, are in contact, the walls forming the joints *a*, *a''*, are somewhat 35 separated. In the ordinary step-joint and miter joint rings we have but a single lap joint to arrest the flow of the gases. In 40 my invention we have a plurality of lap-joints (*a'*, *a'*,) parallel to the sides of the ring, with the surfaces forming the joints in permanent engagement so that the improved ring serves as an effective barrier to the 45 passage of the gases, thereby improving the efficiency of the engine.

45 In the form of ring above described the engaging faces forming the lap joints *a'*, *a'*, are disposed substantially parallel to the sides of the ring, that is to say, in planes at right angles to the axis of the ring. I 50 do not however wish to be understood as limiting the invention in that regard, and in Figs. 9, 10 and 11, I show a ring 1' with these engaging faces disposed at an incline to the sides of the ring and hence at an 55 angle (other than a right angle) to the axis of the ring. The resulting tongues *t'* in that event will be thicker on one side than on the other, the depths of the recesses *d'* being correspondingly affected. Again, while in the 60 main form the angles made by the face *e* with the inner face of the tongue *t* and the bottom of the recess *d* are substantially forty-five (45) degrees, I do not wish to be restricted to this particular angle or to the 65 degree of inclination of the joint *a* resulting 70 therefrom. Thus, in Fig. 12 is shown a form in which the angle *i'* is substantially thirty (30) degrees, and in Fig. 13 we have an angle *i''* less than thirty (30) degrees. Again, while in the forms thus far described 75 the angles are shown sharp they may be rounded as shown at *m* in Fig. 14. In this figure it will also be observed that the free end of the tongue *t''* is substantially in alignment with the offset *n''* forming the terminal 80 wall of the recess *d''* on the same end of the ring, whereas in all the preceding forms it is the base of the tongue that is in alignment with the offset forming the terminal 85 wall of said recess. In other words, in the 80 forms shown in Figs. 1 to 13 inclusive the tongues and their coöperating recesses are relatively longer than are the corresponding parts in Fig. 14, the farthest projecting formation in the last modification being the 90 rounded corner formed at the outer end of the bottom wall of the recess *d''* with the inclined face leading therefrom to the base of the tongue *t''*.

Obviously, the details may be changed in 90 other particulars not herein mentioned without in any wise involving a departure from the nature or spirit of the invention. For example, in each of the several forms described and shown there is but one diagonal 95 joint, and two parallel lap joints (such as *a'*, *a'*,) disposed parallel to the sides of the ring and transverse to the axis of the ring. It is obvious however that a greater or different number of these joints or their equivalents 100 would not necessarily involve a departure from the invention, the basic principle of which is the construction of a ring with a plurality of lap joints substantially parallel to the sides of the ring and transverse to the axis thereof, said joints being 105 connected by diagonal joints inclined to the sides of the ring.

Having described my invention what I 110 claim is:

1. A one-piece piston ring comprising a resilient split metal band terminating at each end in a tongue flush with one side of the band, and in a recess offset from the opposite side, the tongue of one terminal being 115 on the same side as the recess of the opposite terminal and adapted to be received by the recess upon compression of the band to working size, the engaging surfaces of said tongues and recesses being at an angle to 120 the plane of the ring, and suitable formations intermediate the recesses and tongues coöperating to form a lap-joint between the bases of the tongues when received by the recesses, said lap-joint being disposed on a 125 diagonal to the sides of the band.

2. A resilient split metal piston ring comprising a band terminating in formations operating upon compression of the band to working size, to form a plurality of lap 130

joints substantially parallel to the sides of the band, the engaging surfaces of said joints being inclined to the plane of the ring, and diagonal lap-joints connecting the 5 first named joints.

3. A resilient one-piece split piston ring terminating at each end in a tongue flush with one side of the ring, said tongue being thicker on one side than on the other, and 10 in a recess offset from the opposite side, the

base of the tongue being in alignment with the terminal wall or offset of the recess in a direction across the width of the ring.

In testimony whereof I affix my signature in presence of two witnesses.

LOUIS A. SAFFORD.
